UNITED STATES PATENT OFFICE.

GEORGE F. SMITH, OF PLANTSVILLE, CONNECTICUT, ASSIGNOR TO
H. D. SMITH & CO., OF SAME PLACE.

DESIGN FOR CARRIAGE-CLIPS.

Specification forming part of Design No. **7,502**, dated June 23, 1874; application filed February 11, 1874.
[Term of Patent 7 years.]

To all whom it may concern:

Be it known that I, GEORGE F. SMITH, of Plantsville, in the county of Hartford and State of Connecticut, have invented a new Design for Carriage-Clip; and I do hereby declare the following, when taken in connection with the accompanying drawings and the letters of reference marked thereon, to be a full, clear, and exact description of the same, and which said drawings constitute part of this specification, and represent, in—

Figure 1, a side view, and in Fig. 2 an edge view.

This invention relates to a design for the form of articles known to the trade as carriage-clips; and consists in the configuration of the

clip, as shown in the accompanying illustration.

The clip is right-angular, the two sides terminating in screw-threaded ends. Transversely it is flat upon its inside, a narrow flat surface upon the top, and from that inclining to the lower edge—that is to say, substantially one-half hexagon in transverse section.

I claim as my invention—

The design for carriage-clip, the sides and top of which form right angles, and in transverse section are half hexagonal, substantially as set forth.

Witnesses: **GEO. F. SMITH.**
